SVAN NORDEN, OF CRANSTON, RHODE ISLAND, ASSIGNEE TO MOORE FABRIC COMPANY, OF PAWTUCKET, RHODE ISLAND, A CORPORATION OF RHODE ISLAND

DRYING AND FINISHING MACHINE

Application filed February 19, 1929. Serial No. 341,163.

This invention relates to a machine for drying and finishing narrow ware fabrics. Such products, after being woven or knitted, are commonly treated with a starch or size 5 coating, and are then passed through a drying machine in which the strips of fabric are brought in contact with a succession of slowly rotated heated cylinders, by which the fabric is both smoothed and dried and from 10 which it is delivered in uniformly finished condition.

The machines previously used have been well adapted to the drying and finishing of straight fabrics, but are not adapted to finishing curvilinear fabrics, particularly when the curvilinear fabric is of elastic construction.

It is the object of my invention to provide an improved drying machine in which narrow curvilinear fabric, and particularly curvilinear elastic fabric, may be easily, quickly and economically dried and finished, while preserving and firmly establishing its predetermined curvilinear form.

With this general object in view, an important feature of the invention relates to the provision of an improved form of drying cylinder, having a succession of truncated conical surfaces each adapted to receive a separate strip of narrow curvilinear fabric.

Another feature of the invention relates to the provision of squeeze rolls of novel design and construction, by which the excess size or starch may be removed from the fabric 35 without distorting the same or altering its curvilinear form.

Other features of the invention relate to the provision of special delivery rolls, improved guiding devices, and special sizing 40 equipment, and to other arrangements and combinations of parts which will be herein-after described and more particularly pointed out in the appended claims.

A preferred form of the invention is shown 45 in the drawings in which

Fig. 1 is a side elevation of my improved drying machine, with certain shafts and rolls shown in section;

Fig. 2 is a partial rear elevation of the 50 mechanism shown in Fig. 1;

Fig. 3 is a plan view of certain driving connections;

Fig. 4 is an enlarged plan view of my improved squeeze rolls, taken substantially along the line 4—4 in Fig. 1; 55

Fig. 5 is a detail sectional elevation, taken along the line 5—5 in Fig. 4;

Fig. 6 is a plan view of a portion of a drying cylinder, partly in section;

Fig. 7 is a sectional side elevation of the 60 sizing bath and associated parts;

Fig. 8 is a partial plan view of the guiding cylinder in the sizing bath, looking in the direction of the arrow 8 in Fig. 7;

Fig. 9 is a side view of the feed rolls for 65 the sizing bath, looking in the direction of the arrows 9 in Fig. 7;

Fig. 10 is a side elevation of one of the guiding devices; and

Fig. 11 is an end view thereof, looking in 70 the direction of the arrow 11 in Fig. 10.

Referring to the drawings, I have shown a plurality of drying cylinders 20 (Fig. 1) mounted on shafts 21 rotatable in bearings 22, which in turn are mounted upon supports 23 secured to a plurality of upright posts or standards 24. The posts 24 are secured in bases 25 resting upon a suitable foundation and having cross rods 26 extending therethrough and secured in outer or supplementary base members 27. 75

The cylinders 20 are provided with sprocket wheels 30, engaged by a chain 31 passing successively around the sprockets of the several cylinders and also around a chain 85 guide and tension roll 33, a delivery roll 34 and a sprocket 35 on a drive shaft 36. The shaft 36 is rotated by power from any suitable source and the cylinders 20 are thus positively rotated at predetermined speed, 90 with successive rolls rotating in opposite directions.

Adjusting screws 37 are provided for moving the guide-roll 33 to suitably tension the chain 31. A steam pipe 38 (Fig. 2) is 95 connected to each drying cylinder, preferably through the shaft portion 21 thereof, and the cylinders are thus highly heated while permitting their continued rotation.

The cylinders 20 are of the special con- 100

struction most clearly shown in Fig. 6, with the periphery of each cylinder formed with a succession of short truncated conical surfaces 40, separated by abruptly inclined ledges 41 and preferably by very short cylindrical portions 42.

The truncated surfaces 40 are identical in angle and diameter throughout the length of a given cylinder, and the inner surface of the cylinder is preferably given a corresponding outline, as indicated in section in Fig. 6, so that the thickness of metal is substantially uniform throughout the length of the cylinder and the drying coefficient thereof is correspondingly uniform.

It is obvious that the cylinder 20 may be made as a single continuous casting or as a plurality of cylindrical sections suitably secured together and with the joints firmly packed to make the assembled cylinder steam tight.

The pieces of curvilinear fabric F may be presented to the machine in any convenient manner, as in a box or tray 44 (Fig. 1) and are drawn therefrom over a feed roll 45, loosely mounted above a sizing bath or pan 47. The feed roll 45 (Fig. 9) is also formed with a succession of truncated conical surfaces corresponding to the curvature of the fabric to be treated. In view, however, of the greatly reduced diameter of the roll 45, compared with the cylinders 20, the angle of the conical surfaces of the roll 45 is much reduced in order to correspond to the same curvature of the fabric.

Pressure rolls 48 (Fig. 9) are rotatably mounted on brackets 49, which in turn are loosely mounted on a supporting rod 50. The brackets 49 are secured in position by pins 51 extending through slots 52 in the hubs 53 of the brackets 49. The rolls 48 are tapered to correspond to the truncated sections of the roll 45, so that the surface speed of the rolls 48 will substantially correspond to the surface speed of the feed roll 45 at all points of contact therewith.

A guide-roll 55 (Figs. 7 and 8) is loosely mounted in the lower portion of the sizing pan 47, this guide-roll being freely rotatable by the friction of the fabric thereon and being formed with a plurality of truncated conical sections similar to the feed roll 45.

The fabric F passes from the sizing bath to a squeeze roll 60 preferably formed as a succession of rubber-covered truncated conical sections, as indicated in Fig. 4. The roll 60 is mounted on a drive shaft 61, supported in suitable fixed bearings in the frame of the machine.

A pressure roll 64 (Fig. 4) engages each truncated conical surface of the squeeze roll 60 and each pressure roll is also preferably of conical shape and is provided with a relatively thick rubber or cushion surface. The rolls 64 are rotatably mounted on oblique

axes on brackets 65 having guiding portions 66 slideable transversely on a supporting cross bar 67. The cross bar 67 is preferably grooved transversely, as indicated at 68 to receive the guiding portions 66 and direct the movement thereof.

Springs 70 are provided for forcing the brackets 65 and rolls 64 toward the squeeze roll 60 and such inward movement is limited by stop screws 71 threaded in the cross bar 67 and provided with collars 72 (Fig. 5) limiting inward movement of the brackets 65.

The rolls 64 are so designed and proportioned that their peripheral speed will at all points substantially correspond to the peripheral speed of the portions of the squeeze roll 60 engaged thereby. It will also be noted that each pressure roll 64 may be individually and manually adjusted toward or away from the squeeze roll 60.

It is essential that the squeeze roll 60 rotate in a definite speed relation to the rotation of the cylinders 20, but this speed relation is not constant, but varies with the construction and particularly with the thickness of the curvilinear fabric.

In Fig. 3, I have indicated one form of variable speed driving connection between the drive shaft 36 and the squeeze roll shaft 61. The shaft 36 has a chain and sprocket connection 75 to a cone pulley 76, which in turn is connected by a belt 77 to a second cone pulley 78, having a chain and sprocket connection 79 to the squeeze roll shaft 61.

A belt shifting mechanism 82 may be manually adjusted to move the belt 77 axially along the reverse cone pulleys 76 and 78, thus providing any desired speed relation between the cylinder 20 and the squeeze roll 60. Any other suitable or convenient speed changing mechanism may be provided in place of the reverse cone pulleys shown in the drawings.

The delivery roll 34 at the top of the machine (Figs. 1 and 2) is also formed with a succession of truncated conical surfaces, beveled to give the desired relative surface speeds at all points thereof.

Pressure rolls 90 (Fig. 2) are mounted on brackets 91 loosely positioned on a cross bar or supporting rod 92, similar to the pressure rolls 48 and brackets 49 previously described. The rolls 90 are preferably conical and have substantially the same surface speed at all points of contact as the conical surfaces of the delivery roll 34.

It is essential that each strip of fabric engage its conical surface on each drying cylinder at points of corresponding diameter, and it is therefore essential that each strip of fabric be accurately guided as it approaches each drying cylinder.

For this purpose I have provided a separate guide member 100 for each strip of fabric between the squeeze roll 60 and the lowermost drying cylinder 20 and I have

also provided additional guiding members 100 between each successive pair of drying cylinders.

The details of construction of these guiding members 100 are clearly shown in Figs. 10 and 11. The members 100 are mounted on cross bars 102 on which they are secured by pins 103 (Fig. 10) extending through slots 104 and permitting limited independent angular self-adjustment of each guiding device 100.

A piece of narrow fabric F is received in a guideway 105 in each device 100, the guideway being disposed at an angle to the cross bar 102 corresponding to the desired angle of the fabric at the point of guiding engagement. The guideways 105 are preferably open at their upper sides, as indicated at 106 (Fig. 11) to permit easy threading of the fabric therein.

Having described the construction of my improved drying and finishing machine, the method of operation thereof will be readily understood. The strips of curvilinear narrow fabric F are drawn out of the storage receptacle 44 (Fig. 1), over the feed roll 45, and under the guide-roll 55 by the driven squeeze roll 60. The fabric is thus sized or starched and the excess material is squeezed out of the fabric between the squeeze roll 60 and the pressure rolls 64.

The fabric is then delivered to the lowermost drying cylinder 20, passing upward around successive drying cylinders until it reaches the delivery roll 34, from which it is discharged in dried and accurately curvilinear form and from which point it may be cared for in any desired manner.

It will be noted that the curvilinear fabric is supported at every point of contact on surfaces accurately proportioned to the desired curve of the fabric, and that at all points where the fabric is subjected to pressure or tension the engaging surfaces of opposed rolls move at the same speed against each face of the fabric and that the surface speeds are proportionate to the curve of the fabric.

By thus supporting the fabric during the sizing and drying operations, the fabric may be discharged with the exact degree of curvature desired and contemplated in the weaving thereof. This is particularly essential in treating curvilinear elastic fabrics in which the curvature may very readily become distorted if the engaging surfaces do not at all times travel with suitably related surface speeds.

Having thus described my invention and the advantages thereof, I do not wish to be limited to the details herein disclosed, otherwise than as set forth in the claims, but what I claim is:

1. In a drying and finishing machine, a plurality of drying cylinders each having its

outer drying surface formed with a succession of truncated conical portions, and guiding means to present pieces of narrow curvilinear fabric to said cylinders.

2. In a drying and finishing machine, a plurality of drying cylinders each having its outer drying surface formed with a succession of truncated conical portions, guiding means to present pieces of narrow curvilinear fabric to said cylinders, and means to guide said fabric in a predetermined path from each cylinder to a successive cylinder.

3. In a drying and finishing machine, a plurality of drying cylinders each having its outer drying surface formed with a succession of truncated conical portions, and guiding means to present pieces of narrow curvilinear fabric to said cylinders, all of said conical portions in any one cylinder being of identical inclination and diametral dimensions.

4. In a drying and finishing machine, a plurality of drying cylinders each having its outer drying surface formed with a succession of truncated conical portions, and guiding means to present pieces of narrow curvilinear fabric to successive drying cylinders, all of said conical portions in any one cylinder being of identical inclination and identical diametral dimension, and the peripheral wall of each cylinder being of substantially uniform thickness from end to end of said cylinder.

5. In a drying and finishing machine, a plurality of drying cylinders each having its outer drying surface formed with a succession of truncated conical portions, and guiding means to present pieces of narrow curvilinear fabric to successive drying cylinders, said truncated portions being identical in inclination and in diametral dimensions and said cylinders having substantially uniform heat transmitting capacity in all portions of the drying surface thereof.

6. In a drying and finishing machine, a plurality of drying cylinders each having its outer drying surface formed with a succession of truncated conical portions, and guiding means to present pieces of narrow curvilinear fabric to said portions, said guiding means being adjustable to the path of the fabric.

7. In a drying and finishing machine, a plurality of drying cylinders each having its outer drying surface formed with a succession of truncated conical portions, and guiding means to present pieces of narrow curvilinear fabric to said cylinders, said guiding means each being independently self-adjusting to the path of each piece of fabric.

8. In a drying and finishing machine, a plurality of drying cylinders each having its outer drying surface formed with a succession of truncated conical portions, and guiding means to present pieces of narrow curvilinear fabric to said cylinders, said guiding means being independently self-adjusting to the path of each piece of fabric and having a cen-

tral longitudinal threading opening in its upper face.

9. A cylinder for a drying and finishing machine having its outer drying surface formed with a succession of truncated conical fabric-engaging portions.

10. A cylinder for a drying and finishing machine having its outer drying surface formed with a succession of truncated conical fabric-engaging portions, and having its inner surface similarly formed, whereby a substantially uniform peripheral wall thickness is attained.

11. In a drying and finishing machine, a drying cylinder having a succession of truncated conical fabric-engaging portions, and means to guide a piece of narrow curvilinear fabric to an axially predetermined point of engagement with a conical surface of said cylinder.

12. In a drying and finishing machine, means to size a piece of narrow curvilinear fabric, and means to remove excess size therefrom comprising a squeeze roll having a succession of truncated conical fabric-engaging surfaces, and a pressure roll engaging said squeeze roll, said pressure roll having conical surfaces cooperative with said squeeze roll surfaces.

13. In a drying and finishing machine, means to size a piece of narrow curvilinear fabric, and means to remove excess size therefrom comprising a squeeze roll having a succession of truncated conical fabric-engaging surfaces, and a pressure roll engaging said squeeze roll, said pressure roll having conical surfaces cooperative with said squeeze roll surfaces and having substantially the same surface speed as the engaged portion of said

40 squeeze roll at all axial sections of said roll.

14. In a drying and finishing machine, a squeeze roll, a plurality of drying cylinders, and a delivery roll, said rolls being of much less diameter than said cylinders and each of 45 said rolls and cylinders being formed with a plurality of truncated conical portions disposed at such inclinations to their axes that each roll and cylinder will accurately engage and forward a curvilinear fabric of predetermined curvature without curvilinear distortion.

15. In a drying and finishing machine, a squeeze roll, a plurality of drying cylinders and a delivery roll, said rolls being of much 55 less diameter than said cylinders and each of said rolls and cylinders being formed with a plurality of truncated conical portions. the diameter, speed, and inclinations of the conical portions of all of said rolls being so 60 proportioned relative to each other that the relative travel of the long and short edges of a curvilinear fabric engaged thereby will be uniform for all of said rolls.

16. In a drying and finishing machine, a 65 squeeze roll formed with a plurality of truncated

cated conical portions, a separate conical pressure roll engaging each conical portion of said squeeze roll, and means to support each pressure roll for free rotation about an axis so inclined with respect to the axis of said squeeze roll that the surface speeds of said pressure rolls and of said truncated conical portions of said squeeze roll are substantially identical at all points of contact when in driving engagement with each other.

17. The combination in a drying and finishing machine as set forth in claim 16, in which separate means is provided for yieldingly advancing each pressure roll toward said squeeze roll.

18. The combination in a drying and finishing machine as set forth in claim 16, in which said squeeze roll and said pressure rolls are cushion-covered, and in which means is provided for yieldingly advancing each pressure roll toward said squeeze roll, and separate manually adjustable means is provided to positively limit such advance movement for each roll.

19. In a drying and finishing machine, a sizing bath, a guide-roll mounted for free rotation in said bath, rotatable means to deliver a plurality of pieces of curvilinear narrow fabric simultaneously to said bath, and rotatable means to draw said pieces of fabric under said guide roll and from said bath said delivery means, said withdrawing means and said guide-roll each having truncated conical portions engaged by the fabric and corresponding in angle to the predetermined curvature thereof.

In testimony whereof I have hereunto affixed my signature.

SVAN NORDEN.
